UNITED STATES PATENT OFFICE.

WILLIAM MCNAME, OF SUMMIT, NEW JERSEY.

SAFETY BOMB-SIGNAL FOR TRAINS.

1,214,201.

Specification of Letters Patent. Patented Jan. 30, 1917.

Application filed March 21, 1916. Serial No. 85,549.

To all whom it may concern:

Be it known that I, WILLIAM MCNAME, a citizen of the United States, residing at 9 South street, Summit, county of Union, 5 and State of New Jersey, have invented certain new and useful Improvements in Safety Bomb-Signals for Trains, fully described and represented in the following specification and the accompanying drawings, forming 10 a part of the same.

This invention relates to a safety appliance for warning an engineer by a bomb explosion when the train is approaching a danger section of railway track.

15 The invention consists primarily in the provision of a so-called exploding rail to support a bomb at the entrance of a track-section which is to be protected, and a bomb-carrier adapted to set a bomb upon the surface of the exploding rail, a wheel upon the train in addition to the track-rails adapted to run over the exploding rail and thus explode the bomb; and in some cases, of means actuated by the movement of the train-wheels upon the track, to close an electric 20 circuit and produce an actuation of the bomb-carrier.

25 The bomb-carrier consists of a slide movable into and out of a casing adjacent to the exploding rail, and the slide is preferably provided with a weight or spring to move it outward so as to hold the bomb-carrier normally upon the top of the exploding rail.

30 Where the invention is used in connection with danger-signals upon a succession of track-sections, each track-section is provided with one of my appliances which would automatically place a bomb in an operative position when required.

35 The mechanism operates, while the train occupies a block-section, to leave the bomb upon the exploding rail preceding such section; the entrance of the train upon the succeeding section causing an operation of the bomb-carrier to retract the bomb into its casing.

40 The bomb-carrier may be connected mechanically to the signal-arm of a semaphore, or to the mechanism connected therewith, 45 so as to be moved in unison with such signal-arm, the connections operating when the arm is set at "danger" to release the bomb-carrier, so that it may be projected from its

casing by the actuating weight, and the 55 bomb held upon the top of the exploding rail so long as the signal-arm stands at "danger".

The dropping of the signal arm to "safety" operates through the same connections to retract the bomb-carrier into its casing. The bomb-carrier may be connected mechanically to a switch-shifter shaft, arm, or lever, so that when the main-track is opened by shifting the switch and moving 60 the switch-tongues, the bomb-carrier may be released and the bomb moved outward to the top of the exploding rail. The switch-arm or post, when the main-track is thus opened, would display a danger signal, and 65 the connection between such switch-shifter and the bomb-carrier would insure the movement of both in unison, to indicate "danger" or "safety".

70 The exploding rail may be set in any location parallel with the track-rails so that the exploding wheel may travel over it, a spring-mounted wheel being required, but it is preferably set intermediate to the track-rails, and set at least an inch above the same 75 so that the wheel when adjusted to touch the exploding rail and explode the bomb, would move entirely clear of the track-rails at switches and crossings. The frame carrying the wheel is preferably attached to the 80 front of the locomotive or its pilot, so as to give warning before the locomotive has passed the danger point. The wheel may be made movable vertically and a hand-lever provided to raise it above its normal 85 position, so that when the engine is backing or running over a bomb in shunting operations, the wheel may be lifted to clear the bomb.

90 The invention will be understood by reference to the annexed drawing, in which—

Figure 1 is a cross section of a railway track provided with my improvement, and a semaphore tower adjacent thereto; Fig. 2 is a plan of the same parts; Fig. 3 is a plan of 100 the casing for the bomb-carrier with the cover and the slide removed, the shifting-lug upon the slide being shown in section; Fig. 4 is a longitudinal section at the center line of Fig. 3; Fig. 5 is a transverse section across the middle portion of Fig. 4; Fig. 6 is a side elevation of the casing, and Fig. 7 an end elevation of the same. Fig. 8

is a plan of a track-section with a switch and shifter connected to a bomb-carrier; Fig. 9 is an elevation of the explosion rail with the wheel and its frame over the same upon the nose of a cow-catcher; Fig. 10 is a front view of the wheel and its frame; Fig. 11 is a diagram showing an electrical motor agent for shifting the bomb-carrier.

In Figs. 1 and 2, A, A' designate the track-rails, B an explosion rail located between them and set at a higher level; and C is the casing of the bomb-carrier D. E is a semaphore tower having a signal arm F shown in Fig. 1, set to "danger." A battery w^3 is shown adjacent to the semaphore tower, with circuit wire w^4 extended thereto, and lines w^5 and w^6 showing circuit connections to the rails A and A' of the track. This battery and wires represent the usual circuit connections supplied to the danger-signal upon each track-section in a block-system, the circuit being normally open, and closed by the truck-wheels of any passing train, to set the signal at danger. In this invention the bomb-carrier is actuated by a connection to the danger-signal. G designates a movable connection, as a cord or rod, between said signal arm and the bomb-carrier D, the arrangement being such that the connection G is slackened when the arm is set to "danger," and the bomb-carrier then moved forward by a weight or spring to set a bomb a over the explosion rail B, as shown in Figs. 1 and 2.

The bomb-carrier D is shown as a flat slide (see Figs. 3 to 7) movable transversely to the rail B between guides b' in the casing C, and supported upon anti-friction balls c movable in raceways c' beneath the slide.

A lug d is shown projected from the under side of the slide, and a wire rope e is shown clamped in such lug by a screw f , one end being extended over a pulley e' to a weight g movable in a tube g' extended from the bottom of the casing C. The other end of the rope is extended over a pulley h to be united to the semaphore connection G, which is shown effected by a coupling G'.

The bomb a is shown in Figs. 3 and 4 provided with a square shank a' adapted to fit a square hole a^2 in the slide near its outer end. The outward movement of the slide is limited by a stop b' within the casing, see Fig. 4, with which the lug d contacts, at the proper limit, and the inward movement is limited by the contact of the inner end of the slide with the rear end of the casing, as will be apparent from Fig. 4.

A recess i is formed in a hood j upon the front end of the cover c' of the casing, to permit the inclosure of the bomb when the slide is retracted with the bomb thereon. Such would be the normal condition of the device when placed in readiness to be oper-

ated by its connection with the semaphore, whenever the semaphore-arm was set at "danger."

When the semaphore-arm is set at "safety" the tension upon the connection G would act to pull the rope e and retract the slide into the casing, at the same time lifting the weight G into an operative position so that it would project the slide over the rail B, whenever the cord was slackened by the shifting of the semaphore-arm.

A notch o is, in Figs. 3, 4 and 9, shown in the top of the exploding rail B of suitable width and depth to receive the outer end of the bomb-carrier D, and set its upper surface flush with the surface of the rail B, as shown in Fig. 9. The rail B is shown with ends B' sloping downwardly to permit the gradual access of the exploding wheel k to the exploding rail and the bomb a , as is indicated by the arrow k' in Fig. 9. Any projection above the top of the rail D would cause a serious jar to the wheel k when the train is moving at much speed.

The wheel-frame is shown in Fig. 9 attached to the pilot F' of a locomotive, and has a base l with columns m thereon containing springs m' which press downward upon the spindle n of the wheel k . The spindle is thus supported yieldingly upon the train, so as to press the wheel elastically upon the exploding-rail and permit it to rise as it rolls upon the sloping ends B'. The downward movement of the spindle toward the track-rails is limited by means of screws n' in the bottom of the columns m , which may thus adjust the spindle n into any desired relation to the cow-catcher and the rail D.

A yoke g is shown connected by a link g' with a crank r mounted above the wheel k , the crank having a hand-lever r' attached thereto from which a cord r^2 may be carried within reach of the engineer. The crank and yoke serve to lift the axle n so as to clear the bomb a if the locomotive be running backward, as often happens with shunting engines upon main-line tracks. This mechanism thus avoids any unnecessary explosion of bombs, but would not, of course, be used when the train is running forward and liable to enter a dangerous track-section.

The invention is obviously applicable to any train propelled by a motor, as the operation would be precisely the same with an electrical locomotive, or one operated by a gas-fuel engine, as with the ordinary steam locomotive.

Fig. 8 shows the connections between a switch-shifter and its danger signal and the bomb-carrier. The switch points are marked s , s' , and are shown shifted to open the main-line track A, A', and the signal t upon the switch-post u being then turned transversely of the track to indicate danger.

to an approaching train. The rod u' , by which the switch-lever v actuates the switch-points, is connected by a cord v' with the bomb-carrier slide D , so as to hold it retracted when the switch is closed and the signal t turned to "safety"; but operating, as shown in Fig. 8, to slacken the cord when the switch-signal t is turned to "danger", and thus permitting the bomb-carrier to move outwardly so that the bomb would give warning of danger. The switch-signal t and the bomb-carrier thus operate in unison, and the bomb is automatically set to give warning of danger when the main-line rails are open.

The relation of the bomb-carrier to the switch and its signal is thus precisely the same as its relation to the semaphore and its signal; but the invention is also adapted, as shown in Fig. 11, for operating independently of either a semaphore or a switch. Such arrangement requires that the rails of the railway be insulated one from the other and divided into block-sections, and the rails of each section connected respectively to the opposite poles of an electric generator w^2 .

The bomb-carrier is located in the end of such track-section marked A^2 in Fig. 11, and the electric motor agent w is placed in the circuit w' adjacent to the bomb-carrier, and is so connected to the bomb-carrier as to retract the same, as shown in Fig. 11, when the circuit is opened and the succeeding track-section w^3 is clear. When such succeeding track-section is occupied the circuit is closed, as is expressed by the axle and wheels y resting upon the track-rails, and the electric agent then operates to release the bomb-carrying slide, and thus permit the weight g to move the bomb over the rail for exploding.

The motor agent w is shown as an electric solenoid, which is connected to the rear end of the slide d , as in Fig. 8, to pull the bomb-carrier into its casing when the electric circuit is closed, but exerting no action when the circuit is open; and then permitting the weight g to automatically move the bomb-carrier out of its casing to expose the bomb upon the rail.

A sliding bomb-carrier is illustrated to move the bomb to and from the surface of the exploding rail, but it is obviously immaterial what form of bomb-carrier be used, and what form of connections are used to actuate the bomb-carrier and expose the bomb when a train passes the bomb-shifter and enters upon an insulated section of track.

Having thus set forth the nature of the invention what is claimed herein is:

1. In a railway safety appliance, the combination, with an exploding-rail supported parallel with the track-rails, of a bomb-carrier adapted to move a bomb to and from

the surface of the exploding-rail, and a wheel separate from the track-wheels supported yieldingly upon the train to run over the exploding-rail and explode a bomb thereon.

2. In a railway safety appliance, the combination, with an exploding-rail supported parallel with the track-rails, of a bomb-carrier adapted to move a bomb to and from the surface of the exploding-rail, a wheel separate from the track-wheels supported yieldingly upon the train to run over the exploding-rail, and means operated by a train in times of danger for moving the bomb-carrier over the exploding-rail.

3. In a railway safety appliance, the combination, with a system of block-signals indicating danger on track-sections, of an exploding-rail intermediate to the track-rails, a bomb-carrier adapted to move a bomb to and from the surface of the exploding-rail, a wheel-frame carried by the train and supporting a wheel separate from the track-wheels for exploding a bomb upon the exploding-rail, and means for moving the bomb-carrier in unison with the danger-signal.

4. In a railway safety appliance, the combination, with an exploding-rail sustained intermediate to the track-rails, of a bomb-carrying slide movable transverse to the exploding-rail, a wheel separate from the track-wheels supported yieldingly upon the train to press upon the exploding-rail, and such exploding-rail being sloped downwardly at its ends to receive the yielding wheel.

5. In a railway safety appliance, the combination, with the track-rails, of an exploding rail intermediate to the track-rails and set above the level of the same, a bomb-carrier movable to and from the surface of the exploding rail and a wheel carried by the train and held normally above the level of the track-rails to clear the surface of all track-rails, but supported yieldingly to engage the surface of the exploding rail to operate upon the bomb.

6. In a railway safety appliance, the combination, with the track-rails, of an exploding rail intermediate to the track-rails and set above the level of the same, a transverse notch in the top of the exploding rail, a bomb-carrier slide movable into the notch flush with the said rail-top, and a wheel carried by the train and held normally above the level of the track-rails and arranged to elastically engage the surface of the exploding rail to operate upon the bomb.

7. In a railway safety appliance, the combination, with the track-rails, of an exploding rail intermediate to the track-rails and set above the level of the same, a casing transverse to the exploding rail, a bomb-

carrier slide movable in the casing to and from the surface of the said rail, means, as a weight, operating upon the said slide to move it normally over the exploding rail, and a connection to a danger-signal arranged and operated to cause the operation of the weight in times of danger and to retract the slide into the casing in times of safety.

- 10 8. In a railway safety appliance, the combination, with an exploding rail parallel with the track-rails and sustained above the level of the same, of a bomb-carrier adapted to set a bomb upon the top of the exploding rail, and a wheel-frame carried by the train and supporting a wheel at a level to clear all the track-rails, and adapted to press elastically upon the explosion rail and explode the bomb thereon.
- 15 9. In a railway safety appliance, the combination, with an exploding rail parallel with the track-rails and sustained above the level of the same, of a bomb-carrier adapt-

ed to set a bomb upon the exploding rail, a wheel-frame carried by the train and supporting a wheel at a level to clear the track-rails, means for adjusting the level at which the wheel shall be sustained, and means upon the train for manually lifting the wheel to clear the bomb when desired.

10. In a railway safety appliance, the combination, with an exploding rail parallel with the track-rails and sustained above the level of the same, of a bomb-carrier adapted to set a bomb upon the exploding rail, a wheel-frame carried by the train and supporting a wheel at a level to clear the track-rails, springs pressing the wheel normally downward to press the wheel upon the exploding rail, means for limiting the downward movement of the wheel, and means upon the train for manually lifting the wheel to clear the bomb when desired.

In testimony whereof I have hereunto set my hand.

WILLIAM McMANE.
